UNITED STATES PATENT OFFICE.

HARRY ZIMMERMAN, OF FREMONT, OHIO.

SHUTTER-BOWER.

No. 921,784.

Specification of Letters Patent.

Patented May 18, 1909.

Application filed November 5, 1907. Serial No. 400,865.

To all whom it may concern:

Be it known that I, HARRY ZIMMERMAN, a citizen of the United States, residing at Fremont, in the county of Sandusky and State 5 of Ohio, have invented certain new and useful Improvements in Shutter - Bowers, of which the following is a specification.

My invention relates to shutter bowers and consists in certain improvements in the construction of the sill plate, and its combination with the devices carried by the shutter, as fully set forth hereinafter and as illustrated by the accompanying drawing, in which—

15 Figure 1 is a perspective view of a sill plate embodying my improvements; Fig. 2 is an inner face sectional view of a sill and shutter illustrating the sill and sill plate in section in connection with other parts of the device; 20 Fig. 3 is a transverse section on the line 3—3 Fig. 2; Fig. 4 is the same as Fig. 3 showing a different form of locking device; and Figs. 5 and 6 are perspective views of sill plates of somewhat different character from that 25 shown in Fig. 1.

In some forms of sill plates having openings to receive the hook end of a brace rod, the parts are so relatively arranged that a careless carpenter, while securing the plate 30 to the sill so as to be engaged by the catch, will yet fix it so that the rod will not enter the openings to hold the shutter in a proper bowed relation to the sill, but will only hold it when at different angles closing toward the 35 wall, a useless arrangement, as after the shutter is fully opened it requires to be fixed only in one position, that is flat against the wall, which is effected by using a sill plate F with a single opening. To prevent any adjustment which will secure such result I provide the plate B, Figs. 1 to 5, with an opening 3 to receive the locking tongue or bolt, and at each side of this main opening 3 I arrange any desired number of openings 4. 40 As a result when the plate is secured to the sill in position to be engaged by the bolt, there will always be an opening or openings 4 on that side of the main opening 3, where they are required to receive the end of the 45 rod D with the shutter in different positions, closing toward the sill. Generally two openings on each side will with the intermediate opening afford all necessary adjustments of the shutter, but the number may be increased. This construction has the further

advantage that the same form of plate may be used with each shutter, but it will be evident that while the openings on the left of the main opening 3 are engaged by the rod in connection with the right shutter, those at 60 the right will be so engaged by the other rod when the plate is set to coact with the shutter at the left.

While the opening 3 in line with the openings 4 may receive a suitable locking bolt 65 when the shutter is fully closed, I have found it best in many cases to provide an additional opening 5 back of the opening 3, so situated as to receive the bolt or catch, whatever its character, when the shutter is fully closed. 70 This permits the opening 3 to be used for locking the shutter when the latter is nearly, but not quite, closed, and insures such locking in case the presence of ice or snow or the warping of the shutter prevents a complete 75 closure of the shutter.

In the construction shown in Figs. 2 and 3 the locking device consists of the hook at the end of the brace rod which is then supported by the perforated tongue c of a bracket C secured to the shutter, but it may be a sliding bolt, or a pivoted catch D supported by the shutter, as in Fig. 4.

When the locking device is carried permanently with the shutter the openings 3, 5 85 may be both formed to closely fit the bolt, but when the bolt is the end of the rod A, as in Figs. 2 and 3, then the shifting of the position of the locking end as the shutter is carried from a closed position requires an elongation of the opening 3 as shown in Figs. 1, 5 and 6. The arrangement of holes on opposite sides of the main hole 3 may be used in connection with sill plates of cast or malleable metal constructed to be set onto the sill 90 as usual, or into the sill as shown in Figs. 2, 3 and 4, but the arrangement of the locking hole 5 back of the hole 3 may be employed, whether the hole 3 is used with the holes 4 on both sides, as in Figs. 1 and 5, or all at one 100 side, as in Fig. 6, and either arrangement may be used with different forms of locking devices.

The entire plate may not be widened to receive the opening 5, as it may be in an extension 6 of the plate as in Fig. 5.

A form of plate economically produced is that shown in the drawing and consisting of a plate of metal of L-shape in cross section with screw openings either within the regu- 110

lar outline of the top plate *a* as in Fig. 1, or in ears extending therefrom as in Figs. 5 and 6. This sill plate may be a casting, but preferably is bent from a perforated plate of malleable metal, and it will be seen that a flat plate may have all of the perforations punched in it at a single operation, and the plate may then be bent up into shape to form the top plate *a* and face plate *b* and thus cheaply manufactured. It will further be seen that the sill plate thus constructed, when set in a socket of the sill, as shown in Figs. 2, 3 and 4 has its top plate *a* flush with the sill so that there are no projections above the latter, and that the face plate *b* closes the socket *x* in the sill. In order to prevent accumulation of moisture or dust within the socket, I prefer to punch or otherwise form one or more openings 8 in the vertical face plate *b*, the said opening or openings being in a position to allow all of the water or dust to escape from below the top plate *a*. It will be seen that in either of the said constructions there is a face plate with openings to receive the end of the brace rod and engage the catch, and that when L-shaped in cross section it has a flange to close a socket in the sill, and that it can be made of comparatively light material inasmuch as the sides of the socket serve to brace the parts of the sill plate, and that it is cheaply manufactured and readily applied, and presents no obstructions above the face of the sill.

I do not here claim the details of construction shown herein and also shown and claimed in my applications for Letters Patent Serial Nos. 347,531, 400,653 and 401,024.

Without limiting myself to the precise constructions and arrangements shown, I claim—

1. A sill plate provided with bowing openings and with two locking openings, one in line with the bowing openings and the other

back of the first, and each adapted to receive the locking means.

45

2. A sill plate provided with an opening for engaging a locking bolt or catch, and a plurality of bowing openings on opposite sides of the main opening for the purpose specified.

50

3. A sill plate provided with an opening for engaging a locking bolt or catch, and additional openings on opposite sides of the main openings, and a locking opening back of the main opening, for the purpose specified.

55

4. The combination in a shutter bower of a brace rod having a hooked arm, a perforated tongue, both carried by the shutter, and a sill plate provided with a locking opening and a plurality of bowing openings adjacent thereto and with a separate locking opening back of the first, both locking openings in position to receive the end of the brace rod in locking a shutter.

65

5. A sill plate L-shaped in cross section having its top plate with openings for the end of a brace rod, and with a face plate at right angles to the top plate.

70

6. A sill plate having a top plate with openings to receive the end of a brace rod, and a vertical face plate with notches, as set forth.

7. The combination in a shutter bower of a hooked brace rod and means for hinging it to a shutter, a bracket adapted for attachment to the shutter and having a perforated tongue, a sill plate having an elongated locking opening, and bowing openings on each side of the locking opening.

75

In testimony whereof I affix my signature in presence of two witnesses.

HARRY ZIMMERMAN.
